UNITED STATES PATENT OFFICE

144,597

DESIGN FOR A CLAMP

Harry Tomassini, Marion, Ohio

Application August 22, 1945, Serial No. 121,576

Term of patent 14 years

(Cl. D17—6)

To all whom it may concern:

Be it known that I, Harry Tomassini, a citizen of the United States, residing at Marion, in the county of Marion and State of Ohio, have invented a new, original, and ornamental Design for a Clamp, of which the following is a specification, reference being had to the accompanying drawing, forming part thereof.

Figure 1 is a side elevational view of a clamp showing my new design,

Figure 2 is an end elevational view, and
Figure 3 is a plan view thereof.

I claim:

The ornamental design for a clamp, as shown.

HARRY TOMASSINI.
